UNITED STATES PATENT OFFICE.

GEORGE SPENCER NEELEY, OF ST. LOUIS COUNTY, MISSOURI, ASSIGNOR OF ONE-HALF
TO THOMAS O. MOLONEY, OF ST. LOUIS, MISSOURI.

DEVICE FOR MANIPULATING FUSE-BOXES.

1,218,109.

Specification of Letters Patent. Patented Mar. 6, 1917.

Application filed May 22, 1916. Serial No. 99,173.

To all whom it may concern:

Be it known that I, GEORGE SPENCER NEELEY, a citizen of the United States, residing in the county of St. Louis, State of Missouri, have invented a certain new and useful Improvement in Devices for Manipulating Fuse-Boxes, of which the following is a full, clear, and exact description, such as will enable others skilled in the art to which it appertains to make and use the same, reference being had to the accompanying drawings, forming part of this specification.

My invention relates to a special form of implement designed for use in manipulating the fuse plugs of cut-out boxes of the type commonly employed on electrical distribution lines.

It is common practice in electrical distribution systems to employ a fuse box or cut-out which is supported on one of the poles carrying the distribution lines, and within which is housed a fuse which is normally disposed in the circuit from the high tension distribution line to a transformer or a branch line. The purpose of such a device, of course, is to afford protection to the transformer or the branch line, against any abnormal increase in voltage or load on the main line, such as might result from a stroke of lightning or other abnormal occurrence.

As such fuse devices are commonly employed in connection with lines carrying high voltage, and as it is necessary frequently to remove the fuse plug for the purpose of replacing a blown fuse, the linemen whose duty it is to keep the line in operative condition are subjected to a considerable risk by virtue of the proximity of the fuse box to the high potential lines.

It is the purpose of my invention to provide a special form of implement, by use of which, the used fuse plug may be removed without necessitating the operator's working in dangerous proximity to the high potential line.

In the drawings,—

Figure 1 represents a perspective view of the novel portion of my device, and

Fig. 2 represents a vertical section illustrating its mode of operation and use.

Referring to the drawings by reference numerals, let the numeral 1 indicate a pole which is of convenient length to reach the cut-out when manipulated by an operator

standing on the ground. At the upper extremity of this pole is mounted a ferrule 2 which carries a screw-threaded spindle 4 projecting axially. Upon this spindle is mounted by means of interengaging screw threads a clamping member 5. This clamping member includes a nut portion 5^a which forms a base and which is threaded onto the spindle 4 and a hood portion 5^b which is open at one side, and has a top portion 5^c formed with a slot reentrant from the edge of the top at the open side of the hood. This construction forms a flange or lip extending horizontally from the sides of the hood portion toward the axis thereof.

Within the hood portion, and upon the upper extremity of the spindle 4 is revolvably mounted a coöperating clamping member which comprises a cylindrical member 6 and a resilient member 7, the latter being mounted upon the upper surface of the cylindrical member and having its upper surface slightly concaved. This resilient member may be of any suitable material, such as leather or rubber, and it, together with the cylindrical member may be revolvably secured as described, by means of the pintle screw 8.

Extending from the rear portion of the hood portion is a lug 9 in which is mounted a hook 10, the crook thereof being deflected away from the hood portion.

The size of the hood portion and of the reentrant slot in its upper portion are such as to receive the knob end of the fuse plug of the conventional cut-out, and the spacing of the hook member 10 apart from the axis of the hood member is sufficient to accommodate the cut-out box when the knob is seated within the hood member, as illustrated in Fig. 2. In the use of this device, the lineman, who may be standing on the ground, places the hood member over the knob of the desired fuse plug, which comes to proper position against the innermost edge of the reentrant slot, and then rotates the pole to screw the spindle 4 upwardly in the nut portion 5^a. This, of course, operates to bring the coöperating clamping member carried on the end of the spindle into closer juxtaposition to the flange or lip of the hood portion, and thereby to clamp the knob of the fuse plug between the said flange and the coöperating clamping member. When screwed up to the proper ten-

sion to retain the plug in this position, the operator, by pulling downwardly on the pole 1, may remove the plug from the cut-out box, and lower it to within hand reach. 5 When the fuse is renewed, the plug may be replaced in the cut-out box by reversing the operations just described. In screwing and unscrewing the clamping members relative to the fuse plug, the hook 10 forms a stop 10 member which will prevent the rotation of the clamping member 5, and thereby permit the screwing of the spindle into the latter.

By use of this device, it is unnecessary for the linemen to place themselves in dangerous proximity to conductors carrying high potential, it is unnecessary to ascend the pole, and the handling of the fuse plug is facilitated, as it may be removed from its box to the ground without danger of its 20 falling and breaking.

The hook form of the stop member 10 permits the use of the device as a switch hook which is commonly employed in opening fuse boxes, removing fuse switches, and 25 similar operations.

I am aware that the device herein illustrated and described is susceptible of modifications and variations without departing from the scope of my invention as indicated 30 in the following claims.

What I claim is:

1. A device for manipulating electrical fuse plugs comprising a pole, a clamping member supported at one extremity of the 35 pole and movable relative thereto, a co-operating clamping member mounted at said end of the pole and operable relative to the first mentioned clamping member by movement of the pole, and a stop member carried by the first mentioned clamping member and adapted to co-operate with a cut-out box to hold said clamping member against movement upon operation of the co-operating clamping member.

45 2. A device for manipulating fuse plugs of electrical cut-outs comprising a pole, a spindle projecting from one end thereof and revoluble therewith, a clamping member screw-mounted on said spindle and shaped 50 to engage a fuse plug, and a co-operating clamping member mounted on said spindle and movable relative to the first mentioned clamping member by operation of the pole and adapted to engage a fuse block to clamp 55 it against the first mentioned clamping member.

3. A device for manipulating electrical cut-outs including a pole, a spindle sup-

ported at one end thereof, a clamping member having screw-thread engagement on the 60 spindle whereby the two may be moved relatively in a direction longitudinally of the pole, said clamping member having a flange or lip portion of reentrant marginal contour and extending in a direction transversely of the pole, and a co-operating clamping member carried on the spindle and movable toward and from said flange for clamp- 65 ing co-operation therewith.

4. A device of the class described comprising the combination of a pole, a spindle mounted thereon and projecting axially from one extremity thereof, a clamping member having screw-thread engagement with the spindle for movement longitudinally thereon, said clamping member having a transversely extending reentrant clamping lip spaced apart from the extremity of said spindle, a co-operating clamping member mounted on the spindle and movable toward 80 and from said clamping lip by operation of the pole, and a stop member projecting from the clamping member at one side of the axis thereof.

5. A device for manipulating fuse cut-outs comprising a pole, a spindle projecting at one extremity thereof, a clamping member having screw-thread engagement with said spindle for longitudinal movement thereon, said clamping member having a 85 transversely directed clamping flange spaced apart from said spindle, and a co-operating clamping member revolubly mounted on the spindle and movable therewith toward and from said clamping flange.

95 6. A device for manipulating electrical fuse blocks comprising a pole, a spindle movable therewith and projecting axially from the extremity thereof, a clamping member having screw-thread mounting on said 100 spindle, said clamping member being formed with a transversely directed flange spaced apart from the spindle and having an open-sided slot therein in alignment with the pole, and a co-operating clamping member mounted on the spindle and movable therewith by operation of the pole toward 105 and from the clamping flange.

In testimony whereof I hereunto affix my signature in the presence of two witnesses, 110 this 19th day of May, 1916.

GEORGE SPENCER NEELEY.
